UNITED STATES PATENT OFFICE.

JOHN LEMIESZ, OF LARGE, PENNSYLVANIA.

DESIGN FOR A POCKET ARTICLE.

47,492.

Specification for Design.

Patented June 22, 1915.

Application filed February 24, 1915. Serial No. 10,381. Term of patent 7 years.

To all whom it may concern:

Be it known that I, JOHN LEMIESZ, a subject of the Czar of Russia, residing at Large, in the county of Allegheny and State of Pennsylvania, have invented a new, original, and ornamental Design for a Pocket Article, of which the following is a specification, reference being had to the accompanying drawing, forming part thereof.

The figure is a perspective view of a pocket article, showing my new design.

I claim:—

The ornamental design for a pocket article, as shown.

JOHN LEMIESZ.

Witnesses:

SUE B. FRITZ,
LILLIAN BATES.
